(57) **CLAIM**

The ornamental design for a strap mounting bracket, as shown and described.

DESCRIPTION

FIG. 1 is a left side view of the strap mounting bracket, the right side being a mirror image thereof;

FIG. 2 is a top view thereof;

FIG. 3 is a bottom view thereof;

FIG. 4 is an enlarged end view thereof, the other end is a mirror image thereof;

FIG. 5 is a perspective view thereof;

FIG. 6 is a perspective view thereof, shown in an alternate position of use;

FIG. 7 is a perspective view thereof, shown in a second alternate position of use;

FIG. 8 is a perspective view thereof, shown in a third alternate position of use; and,

FIG. 9 is a perspective view thereof, shown in a fourth alternate position of use.

The design is foldable, as shown in views 5 to 9.

1 Claim, 9 Drawing Sheets
